UNITED STATES PATENT OFFICE.

CHARLES S. GOODFELLOW, OF LOWELL, MASSACHUSETTS.

FLUE-CLEANER.

SPECIFICATION forming part of Letters Patent No. 691,718, dated January 21, 1902.

Application filed May 22, 1901. Serial No. 61,373. (No model.)

To all whom it may concern:

Be it known that I, CHARLES S. GOODFELLOW, a citizen of the United States, residing in Lowell, in the county of Middlesex and 5 State of Massachusetts, have invented certain new and useful Improvements in Flue-Cleaners; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 The object of this invention is to provide a simple, convenient, and effective means for clearing or removing from tubes or flues of boilers, and especially vertical boilers, incrustation deposited there by the products 20 of combustion passing through the flues or tubes. Customarily in order to clean the tubes or flues of vertical boilers it is necessary to introduce some scraping instrument into the tubes from the top of the boiler; but 25 this is a tedious and laborious method and, besides, does not result in a thorough cleaning of the tubes. By using the contrivance which I will hereinafter particularly describe 30 and claim access to the tubes may be had from the lower end thereof through the fire-door, and the deposit can generally be removed without the necessity of any scraping of the tubes whatever.

Referring to the accompanying drawings, 35 wherein corresponding letters of reference indicate like parts, Figure 1 is a view of a boiler, partly in section, showing my tube or flue cleaning contrivance in operative position. Fig. 2 is a view in side elevation of the 40 main part of the contrivance, the same being shown partly in section and as introduced into the end of a boiler-tube. Fig. 3 is a view of the end of the contrivance, and Fig. 4 illustrates a modified form of a detail of the invention.

45 In said drawings, *a* designates a boiler having the usual fire-space *b* and fire-door *c*, and *d* denotes the flues or tubes of the boiler.

50 *e f* designate two sections of piping, which are connected together at any angle by an elbow-joint *g*. The free end of the pipe-section *f* carries a coupling *h*, to which may be

connected a flexible pipe or tube *i*, which is in turn connected with some steam-pipe *j*, leading from the boiler *a*. The free end of 55 the section *e* carries a nozzle *k*, having an appreciable taper toward each of its ends.

l designates a cylindrical shell or sleeve which incloses the pipe-section *e* and which has substantially the same length as said pipe-section. At one end the sleeve is secured to the pipe-section by a spider *m*, while its other end (that adjacent the nozzle of the pipe-section) is held in place by another spider *n*, which is formed integral with it and which 65 has a central orifice *o*, which fits over the free end of the nozzle. It should be remarked that the diameter of the sleeve *l* is but slightly greater than the greatest diameter of the nozzle *k*.

70 *p* is simply a flange which is secured rigidly on the sleeve and acts as an abutment, against which the end of the boiler-tube being cleaned takes when the implement is in operative position, as seen in Fig. 1.

75 *q* denotes the handle, it being connected with the pipe-section *f*, preferably at an acute angle thereto, by means of a union *r*, which is adjustably fixed on the pipe-section by a set-screw *s*.

80 In operation, the flexible tubing *i* having been connected up with the steam-pipe *j* and the implement having been introduced through the fire-door *c* and its free end inserted into one of the flues, the steam is turned 85 on. In being discharged from the nozzle and forced violently through the boiler-tube being operated on it not only acts to soften the deposit, but to forcibly remove the same. At the same time it tends to produce a vacuum 90 in the sleeve *l*, the consequence being that atmospheric air is drawn in through the shell and through the tube being cleaned after the steam. The action of the air is not only in augmentation of that of the steam in cleaning out the tube, but serves to dry out the condensation left in the tube by the steam and which if left in the tube would under heat 95 tend to injure the latter.

100 By forming the nozzle with a taper at each end, so that its middle portion is bulged in form, and making the sleeve of a diameter but slightly greater than said middle portion of the nozzle the air is discharged from the

sleeve at points next adjacent the inner surface of the tube or flue, points where it should be discharged in order to get the best results. The action just referred to is of course augmented by the tapering of the rear end of the nozzle.

Referring to the modification shown in Fig. 4, which is designed with a further object of augmenting the action of the air, the nozzle is formed with a series of external spiral ribs *t*, the effect of which will be to discharge the air through the tube or flue in currents of spiral form.

If desired, and with the object of forcing the steam and air through the tubes or flues in a series or succession of impulses, so as to facilitate the loosening action, a valve *u*, having a handle *v*, may be provided, being arranged to control the passage through pipe-section *f*.

Having thus fully described my invention, what I claim as new, and desire to secure by Letters Patent, is—

1. In a boiler tube or flue cleaning apparatus, the combination of a tubular structure adapted to be introduced at one end into the tube to be cleaned and to be connected at its

other end with a source of steam, an air-conducting sleeve inclosing and carried by said tubular structure and open at the end thereof adjacent the discharge end of said tubular structure, a spider formed integral with the open end of said sleeve and fitted onto the discharge end of said tubular structure, and another spider spacing the other end of said sleeve and said tubular structure, substantially as described. 30

2. In a boiler tube or flue cleaning apparatus, the combination of a tubular structure adapted to be introduced at one end into the tube to be cleaned and to be connected at its other end with a source of steam, a nozzle on said first-named end of the tubular structure, an air-conducting sleeve inclosing said nozzle and open at both ends, and spiral ribs interposed between said nozzle and the sleeve, substantially as described. 40

In testimony that I claim the foregoing I have hereunto set my hand this 17th day of May, 1901.

CHARLES S. GOODFELLOW.
